UNITED STATES PATENT OFFICE.

EMERY M. HAMILTON, OF NEW YORK, N. Y.

LEVER-MOVEMENT FOR TYPE-WRITERS.

SPECIFICATION forming part of Letters Patent No. 357,668, dated February 15, 1887.

Application filed April 1, 1886. Renewed December 2, 1886. Serial No. 920,539. (No model.)

To all whom it may concern:

Be it known that I, EMERY M. HAMILTON, of the city of New York, in the county and State of New York, and a citizen of the United States of America, have invented a new and useful Lever-Movement for Type-Writers, of which the following is a specification, reference being had to the accompanying drawings, forming part of the same, in which—

10 Figure 1 is a side elevation, partly in section, and Fig. 2 a plan or top view, of the parts constituting a lever-movement that embodies my invention. Fig. 3 is also a side elevation, partly in section, of the same device, showing the lever in a position different from that shown in Fig. 1; and Fig. 4 represents a modification of the key-board and its connections.

15 The purpose of the lever herein shown and described is to support and move the printing-type in a type-printing machine, so that the type is lifted from an inking-pad and carried to the point where the impression is to be made on the paper and pressed against the paper and then returned to the said pad by a

20 single vibration of the key-lever; and the invention consists in the combination, hereinafter described and claimed, of a type-lever carrying a printing-type and arranged to rock and slide on a fixed fulcrum, a rock-shaft and 25 single crank-arm from which motion is communicated to said lever, a printing-table, and a finger-key, and the described connections with the rock-shaft whereby, in conjunction 30 with a spring, a rocking motion may be given 35 to the rock-shaft.

A is the type-lever. B is a crank fixed on a rock-shaft, C, that is journaled in suitable uprights, as at a a'. The said lever and crank are jointed together; as at b, and c is a keeper 40 or staple fixed in a suitable support, as at d, and through which the lever A passes. It forms the fulcrum of the said lever.

D is a finger or key lever, hinged at its inner end, as at e, and provided at its opposite 45 end with a finger-piece, f.

A' is a table upon which the parts are mounted.

g is a band, one end of which is connected to the crank B, as at g', and the opposite end 50 to the key-lever D, as at g", the said belt passing from its connection down over the inner face of the shaft C.

h is another belt, connected at one end also to the crank B, as at g', and, passing down over the opposite or outer face of the shaft C, is 55 connected at its lower end to a spring, E, which acts through the said belt to rock the said shaft and its attached crank in a direction reverse from that given to it by the key-lever D, through the belt g, and into the position shown 60 in Fig. 1.

F is intended to represent a section of an inking-pad for inking the type j, fixed in the end of the lever A, and G indicates a section of a platen, against which the type on the end 65 of the lever is pressed to give the printing-impression upon paper to be laid against the face of the said platen.

The operation of the described lever movement is obvious. Fig. 1 shows the same in the 70 normal position, at rest. Now, when the key-lever D is depressed by pressing on the finger-piece f the shaft C is rocked on its bearings and the crank B makes a half-revolution, or nearly so, into the position shown by the dotted 75 lines at B'. While the crank is making this movement the free end of the lever A, carrying the type j, describes the curve shown by the dotted line at k, whereby the type at the beginning of the movement is carried directly 80 or nearly directly downward, away from the inking-pad, and at the end of the movement directly upward against the platen for making the printing-impression. Then, when the key-lever D is released, the spring E acts to rotate 85 the crank in the opposite direction, reversing the movement of the lever A and bringing the type back into contact with the inking-pad.

Fig. 4 shows a modification of the key-lever which I regard as the equivalent of that shown 90 in the other figures, and which may be used if preferred. It consists of a post or shaft, m, arranged to slide vertically in suitable supports, and to the lower end of which the belt or band g is attached and the upper end of 95 which is provided with a finger-piece, f. It is obvious that by depressing this post the same effect will be produced as by depressing the key-lever D.

As before intimated, the described lever-movement is especially designed and adapted to operate the type in a type-writing machine in which a series of levers is employed, each one carrying a type. In such a machine the

series of these type-levers may be arranged in a plane in a circle and radiating outward from the type ends, so that each lever, when actuated by the depression of the type-lever, will carry 5 the type to the center of the circle.

By reversing the position on the shaft C of the bands *g* and *h*, it is obvious that the movement of the lever A may be reversed, so that when the lever A is at rest under the stress of 10 the spring E its type end would lie in contact with the platen G, and the manipulation of the key-lever would carry the type from that position outward to the place of the pad F and back again to the platen. Such an arrangement would not be suitable for a machine in which the type-levers are arranged in a circle and the printing is done at the center of such circle; but the described lever movement is also adapted to the use of a single lever 15 to give repeated impressions with a single type, or the use of a series of such levers arranged side by side parallel to each other, and when thus used the described reverse move-

ment may be adopted, the positions of the inking-pad and platen being also reversed. 25

I am aware that vibrating and reciprocating type-levers have been used in type-writing machines, to which motion has been communicated in various ways and by various devices for both inking the type and making the 30 printing-impression. I do not therefore claim, broadly, such a lever-movement, but limit my claim to the special devices and combination claimed.

What I claim as my invention, and desire to 35 secure by Letters Patent, is—

The combination of the type-lever A, adapted to carry at its free end a printing type, a fixed fulcrum, *c*, rock-shaft C, single crank-arm B, secured on said shaft and hinged to said lever, 40 with the described means for rocking said shaft, as and for the purpose set forth.

EMERY M. HAMILTON.
